UNITED STATES PATENT OFFICE.

ALBEN E. LUNDELL, OF NEW YORK, N. Y., ASSIGNOR TO WESTERN ELECTRIC COMPANY,
INCORPORATED, OF NEW YORK, N. Y., A CORPORATION OF NEW YORK.

TELEPHONE-EXCHANGE SYSTEM.

1,271,186.

Specification of Letters Patent.

Patented July 2, 1918.

Application filed November 13, 1916. Serial No. 131,046.

To all whom it may concern:

Be it known that I, ALBEN E. LUNDELL, a citizen of the United States, residing at New York, in the county of Bronx and State 5 of New York, have invented certain new and useful Improvements in Telephone-Exchange Systems, of which the following is a full, clear, concise, and exact description.

This invention relates to telephone exchange systems, and more particularly to telephone systems in which an operator's telephone set may be automatically associated with a calling subscriber's line in response to the extension of such line to a link 10 circuit used in establishing a connection.

It is the object of the present invention to provide means whereby the calling party may attract an operator's attention after a listening key switch operated in response to 15 the extension of the calling line, has been moved into its listening-out position.

The drawings disclose enough of a telephone exchange system to enable one skilled in the art to understand the present invention. The invention is applicable to systems of a widely varying character but in 20 its preferred embodiment is adapted for use in the semi-mechanical telephone system disclosed in patent No. 1,168,319.

30 A subscriber at station A desiring to obtain a connection removes his receiver from the switchhook, whereupon a line relay 1 becomes energized and causes the lighting of a signal 2 for attracting an operator's attention. The operator, noticing the signal 35 lighted, inserts a plug 3 into an answering jack 4 of the calling subscriber's line, whereupon relays 5, 6 and an answering supervisory relay SR become energized in the well-known manner. Relay 5 disconnects 40 relay 1, thus causing the extinguishing of lamp 2. Relay 6 closes a circuit from ground through its armature and front contact, a contact 7 and the power magnet of a 45 listening key sequence switch 8, to grounded battery. Under the control of its normal contact 9, the listening key sequence switch is moved out of position 1 into its listening-in position 7.

50 The operator's telephone set 10 is now connected in circuit with the calling subscriber's station through sequence switch con-

tacts 11 and 12, talking battery being supplied from repeating coil R through cord C.

When the sequence switch 8 moved into 55 position 2, a circuit was closed from ground, through the armature and front contact of relay 6, sequence switch contact 13, a contact 14 and the power magnet of a sequence switch 15, to grounded battery. Under the 60 control of its normal contact 16, the sequence switch 15 is moved out of position 1 and into position 2. The sequence switch 15 controls the operation of a selector switch by means of which the cord C may be extended toward a called subscriber's station B. The sequence switch 15 controls the 65 association of a sender with the selector switch for controlling its operation in accordance with the numerical designation of the called line. The setting of the selector switch is accomplished while the sequence switch 15 is resting in various positions between 2 to 16, in which positions it may be moved under the control of contacts actuated 70 at the sender. In the present case it will be assumed that by closing a contact 17 at the sender, the sequence switch 15 is moved out of position 2 and into position 16.

75 After the call has been received, the operator depresses her listening-out key LO, closing thus a circuit from ground, through the contact of key LO, a contact 18 and the power magnet of sequence switch 8, to grounded battery. The sequence switch is then moved into its listening-out position 11, in which position the telephone set 10 is disconnected from the line.

80 If for any reason the operator desires to listen in again on an established conversation, she depresses her listening-in key LI, causing thus the energization of a relay 19. The relay 19 closes a locking circuit for itself through sequence switch contact 20 and its right-hand armature, and through its left-hand armature a circuit including sequence switch contact 21 for moving the sequence switch 8 out of position 11 and through position 12 into position 1. The 85 relay 6 being energized at this time, the sequence switch 8 will be immediately moved into position 7 in the above described manner and the operator's telephone set 10 is 90 thus again connected to the cord C.

If the operator leaves sequence switch 8 in its listening-in position 7 and uses another sequence switch 8' for connecting her head set through contacts 11' and 12' of this 5 sequence switch to another cord circuit similar to C, then as soon as sequence switch 8' moves into position 2 and closes its contact 30', a circuit is closed from ground through this contact 30', contact 31 and the power 10 magnet of sequence switch 8, to grounded battery, for moving sequence switch 8 out of position 7 and into position 11. In the same manner, sequence switch 8' may be moved out of its listening-in position upon 15 the closure of contact 30 of sequence switch 8. The sequence switch 8' may also be controlled by the key LO through its contact 18'.

If the calling subscriber desires to 20 call the operator after the connection has been established, he will momentarily depress his switchhook, causing thus the momentary deenergization of relay SR. Assuming that the sequence switch 8 is in its 25 listening-out position 11, a circuit is closed from grounded battery, through the power magnet and contact 32 of sequence switch 8, the armature and back contact of the supervisory relay SR, and a contact 33 of the 30 sequence switch 8 to ground. Due to the closure of this circuit, the sequence switch is moved into position 12, whereupon in response to the subsequent energization of relay SR a circuit is closed from ground, 35 through a lamp 34, the armature and front contact of relay SR, sequence switch contact 35 and an interrupter 36, to grounded battery. Under the control of the interrupter the lamp is caused to flash. As soon 40 as the operator notices the lamp flashing, she depresses the listening-in key LI and causes the movement of the sequence switch 8 into position 7 in the above described manner.

45 If the listening key sequence switch 8 was standing in position 7 when the calling subscriber caused the momentary operation of the relay SR for the purpose of recalling the operator, or if this sequence switch was 50 in any of the positions except 11, then, due to the fact that sequence switch contact 37 is closed, grounded battery is connected through this contact and the back contact of relay SR and lamp 34 to ground, and 55 thus the lamp 34 is caused to light up.

As soon as the sequence switch reaches 60 position 7 the operator will be able to converse with the calling party. If disconnection is desired, then the calling and called subscribers restore their receivers, causing 65 thus the permanent deenergization of the supervisory relays SR and SR'. These relays control the usual clearing-out signal for the operator. Lamp 34 will now be constantly lighted and thus the operator

knows that the calling subscriber does not want to recall her. She then removes plug 3 from jack 4, causing thus the deenergization of relay 5 and 6, whereupon a circuit is closed from grounded battery, through 70 the armature and back contact of relay 6, a contact 40, and the power magnet of sequence switch 8, to grounded battery, for moving the sequence switch out of position 11 and through position 12 into position 1. A circuit is then closed from 75 grounded battery, through the armature and back contact of relay 6, a sequence switch contact 41, a contact 42 and the power magnet of sequence switch 15, to 80 grounded battery, for moving this sequence switch into its normal position.

What is claimed is:

1. In a telephone exchange system, a line, a trunk, means for extending said line to 85 said trunk, a variably operable switching device having a listening-in and a listening-out position, a signal, means operated upon the extension of said line to said trunk for moving said switching device into 90 the listening-in position, means for moving said switching device into the listening-out position, means for moving said switching device out of said listening-out position, and means operative thereupon for 95 actuating said signal.

2. In a telephone exchange system, a subscriber's line, an operator's trunk circuit, means for extending the line to said trunk circuit, a variably operable switching device having a listening-in and a listening-out position, means responsive to the extension of said line for moving said device into the listening-in position, means for moving said device into the listening-out position, operator controlled means for moving said device out of said listening-out position, and subscriber controlled means for moving said device out of the listening-out position.

3. In a telephone exchange system, a subscriber's line, an operator's trunk circuit, means for extending said line to said circuit, a listening key switch movable to a listening-in and listening-out position, a signal associated with the trunk, operator controlled means for moving said switch out of the listening-out position, subscriber controlled means for moving said switch out of the listening-out position, means controlled by said switch when moved out of the listening-out position for actuating said signal, said last mentioned means being operative only when said subscriber controlled means is actuated.

4. In a telephone exchange system, a line, a trunk, a calling signal associated with said line, operator-controlled means for extending the line when calling to said trunk, a recall signal at said trunk, a vari-

ably operable switching device associated with said trunk and having a normal, a listening-in and a listening-out position, means for moving said switching device 5 into said listening-in position in response to the extension of said line to said trunk, manually operable means for moving said switching device from its listening-in to its listening-out position, and means controllable through the calling line to operate 10 said switching device for actuating said recall signal.

In witness whereof, I hereunto subscribe my name this 11th day of November, A. D. 1916.

ALBEN E. LUNDELL.
